(57) **CLAIM**

The ornamental design for a combined ball device and a portion of a drinking vessel, as shown and described.

DESCRIPTION

FIG. 1 is a perspective view showing the combined ball device and a portion of a drinking vessel embodying the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view showing a second embodiment of the combined ball device and a portion of a drinking vessel;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a perspective view showing a third embodiment of the combined ball device and a portion of a drinking vessel;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top plan view thereof;

FIG. 21 is a bottom plan view thereof;

FIG. 22 is a perspective view showing a fourth embodiment of the combined ball device and a portion of a drinking vessel;

FIG. 23 is a front elevation view thereof;

FIG. 24 is a rear elevation view thereof;

FIG. 25 is a left side elevation view thereof;

FIG. 26 is a right side elevation view thereof;

FIG. 27 is a top plan view thereof;

FIG. 28 is a bottom plan view thereof;

FIG. 29 is a perspective view showing a fifth embodiment of the combined ball device and a portion of a drinking vessel;

FIG. 30 is a front elevation view thereof;

FIG. 31 is a rear elevation view thereof;

FIG. 32 is a left side elevation view thereof;

FIG. 33 is a right side elevation view thereof;

FIG. 34 is a top plan view thereof;

FIG. 35 is a bottom plan view thereof;

FIG. 36 is a perspective view showing a sixth embodiment of the combined ball device and a portion of a drinking vessel;

(Continued)

FIG. 37 is a front elevation view thereof;
 FIG. 38 is a rear elevation view thereof;
 FIG. 39 is a left side elevation view thereof;
 FIG. 40 is a right side elevation view thereof;
 FIG. 41 is a top plan view thereof; and,
 FIG. 42 is a bottom plan view thereof.
 The broken lines in the drawing views depict environment that forms no part of the claimed design. The dot-dash broken lines illustrate a boundary of the claim and forms no part of the claimed design.

1 Claim, 28 Drawing Sheets
